UNITED STATES PATENT OFFICE

WILLIAM H. RUSSELL, OF NEW HAVEN, CONNECTICUT

COIN ACTUATED CHANGE MECHANISM

Application filed June 30, 1924. Serial No. 723,213.

This invention relates to change making machines, and it is especially designed for the purpose of returning change or coins of smaller denomination for a coin of larger denomination deposited in the slot of the machine. The amount of change returned is automatically determined by the size of the coin deposited in the machine, thus five pennies are returned for a nickel, a nickel and five pennies for a dime, a dime, two nickels and five pennies for a quarter, and a quarter, a dime, two nickels and five pennies are returned for a half-dollar. It will be obvious as the description proceeds that the device is calculated to serve not only as a change making mechanism, but may also be used to deduct any desired amount from the deposited coin so as to collect a fare, and return the balance, when a coin is deposited. The device may, therefore, be used as a fare collector as well as a change machine, and for this reason is particularly applicable for use in connection with pay-as-you-enter cars, so as to avoid the necessity of conductors handling any of the passengers' money, and in fact, may do away entirely with the services of the conductor and thus lessen the cost of operation of the cars.

One object of the invention, therefore, is to provide an improved change making machine which will be simple in construction and operation, and while serving to make change for all denominations of coins will be relatively economical to manufacture.

A further object of the invention is the provision of a device of the character described which will be relatively economical to manufacture and which will, at the same time, operate efficiently and accurately to automatically return a given amount of change for any coin deposited therein.

A still further object of the invention is the provision of a change making machine for automatically returning change for coins of various denominations, in which all of the coins may be inserted through a common slot, the coins being properly handled by the machine after their deposit therein so that the proper amount of change is returned.

A still further object of the invention is to provide a machine of this character which may be adjusted so as to select the coins very accurately according to their size, in order that the proper amount of change will be returned, and will return to the depositor any coin which the machine is not designed to handle, such as pennies, for example, for which no change would be given and which would not be sufficient to pay a fare.

Other objects of the invention are to provide a machine of this character which may not be operated by slugs and various imitation coins which people sometimes attempt to use in such machines, and to provide a machine which will automatically be closed against further operation when the supply of change coins therein is exhausted.

To these and other ends, the invention consists in the novel features and combination of parts to be hereinafter described and claimed.

In the accompanying drawings:

Fig. 1 is a perspective view of a coin actuated change machine embodying my improvements;

Fig. 2 is a top plan view of the machine with the cover removed to expose the interior mechanism;

Fig. 3 is a side view of the interior mechanism of the machine, the case being shown in section;

Fig. 4 is a view similar to Fig. 3 but taken from the opposite side of the machine, and showing the parts in a different position;

Fig. 5 is a sectional view on line 5-5 of Fig. 2;

Fig. 6 is a sectional view on line 6-6 of Fig. 2, showing the progress of a coin through the machine;

Fig. 6^a is a detailed view;

Fig. 7 is a sectional view on line 7-7 of Fig. 2;

Fig. 8 is a sectional view, looking in the opposite direction, on line 8-8 of Fig. 2;

Fig. 9 is a rear elevational view of a modification of my machine, and,

Fig. 10 shows a modified form of coin ejector.

The device which I have selected to illus-

trate and describe as a preferred embodiment of my invention is enclosed in a case 10, provided with a single coin slot 11, through which the coins of all denominations are inserted and through the front wall of which projects an operating handle 12 through which the necessary power is supplied to cause the coin to manipulate the proper mechanism to deliver the required amount of change to the change hopper 13, from which it may be removed by the passenger or depositor of the coin.

As shown more especially in Fig. 6, a plurality of slides 14, 14^a, 14^b and 14^c are movably mounted upon the slideways 15, 15^a, 15^b and 15^c, one of these slides being provided for each denomination of coin which the machine is designed to handle. The slides are provided with coin openings 16, 16^a, 16^b and 16^c which are graduated in size, the largest opening 16 being at the top. The effective size of these openings may be very finely adjusted by means of small leaf springs or the like 17, 17^a, 17^b and 17^c which are adjustably mounted upon the lower faces of the slides so that they may be moved in a direction to cause their ends to project over the sides of the coin openings 16, 16^a, 16^b and 16^c and limit the size of these openings. These springs are secured to the slides adjacent their rear ends so that the front part of the spring enjoys a certain amount of freedom, and if a slug or disk which is heavier than the legal coin of that size, such as a lead slug, for example, is inserted in the machine, the projecting end of the spring will be depressed and permit the coin to pass through the machine without operating it.

Connected to the handle 12 are a number of pushers 19, 19^a, 19^b and 19^c, one being provided for each of the coin slides previously described. The free ends of these pushers extend over and rest freely upon the slides referred to and are provided at their ends with V-shaped notches 20, 20^a, 20^b and 20^c shown more especially in Figs. 6^a and 7 in which are mounted rollers 20^d. The notches being adapted to embrace the edge of the coin and as will be hereinafter explained the rollers push the coin forwardly in the machine and through the coin actuate one of the slides to operate the machine. The pushers are also provided at the rear end of the V-shaped slots with pins 21, 21^a, 21^b and 21^c so that when a coin is inserted in the machine which might be too large to enter the coin opening in any of the slides, it will be pushed off one of the slideways 17, 17^a, 17^b and 17^c and will be returned to the depositor. A guide rod 22 is provided upon the handle and is surrounded by a coiled spring 23 which normally urges the handle to an outward position so that it will be returned to the proper operating position after it has been pushed inwardly.

Above each of the slides 14, 14^a, 14^b and 14^c are provided pairs of guide plates 24, 24^a, 24^b and 24^c spaced apart to such an extent that a coin may enter between them and will be supported upon its edge in a vertical position. While the slides 14, 14^a, 14^b and 14^c form bottom closures for the openings between these plates at the end thereof adjacent the front of the machine, it will be apparent that at the rear end the slots are open so that a coin may drop through the machine freely from one to the other. Pairs of pins 25^a, 25^b and 25^c are inserted between the corresponding plates across the slots provided thereby so as to properly guide the coins so that they will fall downwardly into the coin chute 26 and coin receptacle 27, from which they may be removed through the door 28 which may be locked, as shown at 29, to prevent unauthorized removal of the coins. Upon the top of the case is provided a guide 25, which serves the same purpose as the pins previously described and guides the coin of largest dimension, or half-dollar, as illustrated in the present machine, and causes it to be depressed so that it will fall in the coin chute 26.

As shown in Fig. 2, one of the upper plates 24 is cut away adjacent the coin slot and is replaced by a magnet 32 which acts as a guide in conjunction with the other plate 24, and also serves to attract and hold any iron or steel slug, which unlike a lead slug, would not be sufficiently heavy to depress the ends of the springs 17, etc., but would operate the machine in the same manner as a coin. Swinging detents 33, 33^a, 33^b and 33^c are pivoted at 34, 34^a, 34^b and 34^c to one of each of the pairs of plates 24, 24^a, 24^b and 24^c. These detents are formed to swing to the left as shown in Fig. 6, but are prevented from swinging to the right of the positions shown in that figure by stop pins 35, 35^a, 35^b and 35^c. When a coin is inserted in the machine and falls into the coin opening in one of the slides and is caught by one of the pushers whereby the coin and slide move forwardly, it might be possible to move the slide and coin to a sufficient extent to operate the machine before the coin was pushed downwardly by the pins 25^a, 25^b, etc., and the handle might then be returned to its operating position from which the change mechanism could be again operated by the same coin, and it might be possible for a depositor to get more change than he was entitled to in this manner. With the provision of the swinging detents 33, 33^a, 33^b, etc., such manipulation of the mechanism is not possible, for while the detents may swing to the left of the position shown in Fig. 6 to permit the coin to pass they will not permit it to return so as to again operate the machine, but will push it out of the slot in the slide over the front edge thereof and cause it to fall into the chute 26.

The construction and operation of the various slides 14, 14^a, 14^b by means of coins inserted through the slot 11 and operated by the pushers 19, 19^a, 19^b and 19^c having been described, it will now be explained how the operation of the slides serves to return the proper change to a depositor of a coin.

As shown in Fig. 2 in the particular embodiment of my invention which I have selected to illustrate, there are five coin hoppers 40 at the rear of the device which are, in the particular machine shown, designed to contain pennies. Four other coin hoppers are shown, two of which, 41 and 42, are designed 15 to contain nickels, 43, dimes, and 44, quarters. It will, of course, be understood that various changes may be made in the particular coins for which the chutes are designed according to the denominations of the coins which the 20 machine is designed to handle. A coin ejector 45 is arranged for each of the hoppers 40, the five ejectors all being connected to a bar 46 which is, in turn, connected by means of the arm 47 to the slide 14^b which may be 25 termed the nickel slide, as the slot 16^b therein is calculated to receive and hold a nickel coin in operating position. The ejectors 45 are provided with a shouldered portion 48, adjacent their ends, so that each will catch 30 and eject the lowermost coin in the hopper with which it is associated. It will be apparent, therefore, that when a nickel is inserted in the slot 11 it will fall through the half-dollar opening 16 and quarter opening 35 16^a and will lodge in the nickel opening 16^b in the slide 14^b. The operation of the handle will cause the pusher bar 19^b to engage the edge of the coin and by moving the coin will move the slide 14^b to the left, as shown in 40 Fig. 6. The arm 47 connected to the slide will likewise be moved to the left and will impart a similar movement to the bar 46, which will cause each of the ejectors 45 to 45 eject one coin from each of the hoppers 40 so that the depositor of the nickel will receive five cents in change.

Each of the hoppers 40 is provided with a small opening 50 in one side thereof, and a pawl 51 pivoted at 52 to each of the ejectors 50 45 is designed to catch in the opening 50 when the supply of coins is so low that there is no coin opposite this opening and retain the ejector and the attached slide in their forward positions so as to indicate to any future depositor of coins that the supply is exhausted and the machine will no longer operate. When the nickel slide is in a forward position the coin slot 11 is closed by means 55 of a plate 54, which as shown more especially in Fig. 7, is secured to an arm 58, the arm 58 being secured in turn to the nickel slide 14^b. As will be explained hereinafter, the slides are so arranged that the nickel slide is moved each time the handle 12 is pushed 60 inwardly so that whenever the machine is op-

erated the slot 11 is closed until the slide is returned to its original position. A spring 59 serves the purpose of returning this slide after the machine has been operated. Springs 52^a are arranged upon the pawls 51 to urge 70 them into the openings 50 at the proper time. The openings 50 are usually arranged so that the pawls 51 will catch therein when there is still one coin left in the hopper, as according to the arrangement of the ejectors 48 75 the coins which are delivered to the user of the machine are not always pushed off the ejectors upon the outward movement thereof but are pushed off by the next coin in the hopper upon the return movement of the ejectors. For instance, as shown in Fig. 4, the ejectors have been moved forwardly and the coin, which has been pushed out of the hopper, may remain upon the ejector until the return movement thereof when it is pushed off 80 the ejector by contact with the lowermost coin in the hopper.

The dime slide 14^c is connected by means of the arm 61 with a coin ejector 62 which operates in connection with the nickel hopper 42. The ejector 62 is provided with a spring pressed pawl 63 which operates similarly to the pawls 51 previously described. To the dime slide is also secured an arm 64 which extends upwardly in front of the nickel slide 14^b so as to engage the latter slide and move it forwardly when the dime slide is moved. As has been previously explained, the nickel slide is connected to the five penny ejectors, and the dime slide being connected to one of the nickel ejectors and also arranged to operate the nickel slide, it will be seen that when a dime is inserted into the slot 11 it will drop freely through the mechanism until it engages in the slot 17^c whereby when 135 the handle is moved forwardly it will cause the dime slide 14^c and the nickel slide 14^b to be operated, and the depositor will receive a nickel and five pennies in change.

It may be here stated that if it is desired to collect a fare from the inserted coin instead of returning the entire change to the depositor, any of the ejectors may be disconnected or the coin hoppers removed so that any desired amount may be deducted from the change. 115 For instance, if it was desired to collect a fare of five cents the arm 47 could be disconnected or the five ejectors 45, so that when a nickel was deposited in the machine no change would be returned, and when a dime was deposited in the machine only a nickel would be returned. Likewise, if it was desired to deduct an odd amount, seven cents for instance, from a dime, the nickel ejector 62 and two of the penny ejectors 45 could be disconnected and three cents would be returned to the depositor of a dime in the machine.

The quarter slide 14^a is connected by means of the arm 65 to an ejector 66, which cooperates with the other nickel hopper 41, the

ejector 66 being provided with the spring pressed pawl 67 which operates similar to the pawl 51, and the slide is also connected by means of the arm 68 to the ejector 69 which cooperates with the dime hopper 43 and is provided with the spring pressed pawl 70. To the slide 14^a is also secured a bar 71, as shown in Fig. 5, which extends downwardly and abuts against the rear edges of both the nickel slide 14^b and the dime slide 14^c, so that when the quarter slide is operated both the nickel and the dime slides are also actuated. It will be apparent, therefore, that when a quarter is inserted into the slot 11 and serves to actuate the slide 14^a through the pusher 19^a, the slides 14^b and 14^c will also be operated. The slide 14^b will, as has been previously explained, cause the ejection of five pennies from the hoppers, while the slide 14^c will cause the ejection of a nickel from the hopper 42. The slide 14^a being connected to ejectors cooperating with both the nickel hopper 41 and the dime hopper 43; through the arms 65 and 68, will also cause a dime and another nickel to be ejected and deposited in the change hopper 13. It will be seen, therefore, that the depositor of a quarter receives a dime, two nickels and five pennies in change. Likewise, the half-dollar slide 14 is connected by means of the arm 75 to an ejector 76 which cooperates with the quarter hopper 44, and is provided with the usual spring pressed pawl 77. To the slide 14 is also secured an arm 78 which projects downwardly in front of the quarter slide 14^a so that the quarter slide is actuated whenever the half-dollar slide is moved. It has already been explained that the operation of the quarter slide serves to return twenty-five cents in change to the depositor, and therefore, it will be obvious that the operation of the half-dollar slide which is connected to the quarter slide, and which is also connected to the ejector 76, which cooperates with the quarter hopper will serve to return to the depositor fifty cents in change, the amount consisting of a quarter from the quarter hopper, and a dime, two nickels and five pennies which will be delivered by the actuation of the quarter slide.

It will be obvious from the foregoing description that any desired amount may be deducted from any of the coins if a fare is to be collected, or if not, that the entire amount of change will be returned to the depositor. The coins which are ejected from the various hoppers fall upon an inclined plate 79 which delivers them to the change hopper 13. A guard plate 80 may be arranged above the change hopper to prevent anyone tampering with the mechanism of the device.

The progress of a coin through the machine is shown more especially in Fig. 6, wherein a quarter is illustrated as having been inserted through the slot 11. The coin drops

through the slot 16 and rests within the opening 16^a in the slide 14^a. The handle 12 is now pushed inwardly and the pusher 19 serves to move the slide 14^a forwardly by means of the engagement of the V-shaped notch 20^a upon the end of the pusher with one edge of the coin, the opposite edge contacting with the front edge of the slide. The coin and slide are moved forwardly, the swinging detent 33^a being swung upwardly by contact with the coin so as to permit the latter to pass. As previously explained, the change mechanism will be operated by the forward motion of the slide. The coin is frictionally held between the pusher and the front edge of the slot in the plate 14^a until it strikes the lower of the two pins 25^a by which it is pushed downwardly through the slot in the slide 14^a against the tension of the projecting end of the spring 17^a, the coin falling free from the slide and striking the two lower pins 25^b by which it is guided into the chute 26.

Assuming, however, that the operator tries to push the handle forwardly to a sufficient extent to operate the change mechanism, but not to such an extent as to cause the coin to be ejected from the slide 14^a by the pin 25^a, the return of the pusher and slide by their respective springs will cause the edge of the coin to engage the detent 33^a which has returned by gravity to the position shown in Fig. 6, and the coin will be pushed out of the slot over the edge of the plate 14^a and will strike the upper pin 25^b and be delivered to the chute 26 as before.

If a penny is inserted into the slot 11 such a coin will pass freely through the three slides 14, 14^a and 14^b and will lodge in the slot in the plate 14^c but will not enter such slot to a sufficient extent to cause the pusher to operate the slide. On the other hand, when the pusher 19^c is moved forwardly, the contact of the coin with the edge thereof and with the pin 21^c will cause the coin to roll forwardly over the front edge of the slide 14^c and fall upon the plate 79 instead of into the chute 26, so that the coin will be returned to the operator.

Substantially the same operation will take place if a lead slug were inserted into the slot 11. Such a slug would be sufficiently heavy to overcome the tension of any of the springs 17, 17^a or 17^b so that the coin would not be retained in a slot of the proper size in any of the plates but would drop freely through the device until it lodged in a slot which was too small to allow the entry of the slug to a sufficient extent to operate the slide so that it would be acted upon in the same manner as a penny when caught in the slot in the dime slide. For instance, if a lead slug the size of a quarter were inserted, this would not be retained by the spring 17^a as would be the case if a quarter were inserted, as shown in Fig. 6, but would be allowed to drop upon the

nickel slide 14^b where, upon actuation of the pusher 19^b, it would be pushed over the edge of the slide and returned to the depositor.

If, however, a steel or iron slug were inserted in the machine, such a slug would be caught by the magnet 32 and would be pushed off the magnet by the pin 21 and fall freely between the plates 24, 24^a, etc. prior to its reaching the edge of the slot 26, so that it would fall upon the plate 79.

It will be obvious that as the nickel slide 14^b is moved whenever the machine is operated by a coin of any denomination, it will only be necessary to connect the closure plate 54 which closes the slot 11 with the one slide, and likewise it will only be necessary to connect the slide returning spring 57 to the nickel slide, as all of the other slides are provided with arms which abut the front edge of the nickel slide so that the return of the latter will effect the return of all of the other slides.

In Fig. 9 of the drawings I have shown a slightly modified form of my invention wherein individual coin chutes 26^a, 26^b, 26^c and 26^d are provided so that the coins of each denomination are caught separately and delivered to separate compartments 27^a, 27^b, 27^c and 27^d from which they may be removed.

In Fig. 10 of the drawings I have shown a modified form of ejector mechanism which serves to eject the coin upon the outward stroke instead of upon the return stroke as is the case with the ejectors shown in connection with Figs. 1 to 8 of the drawings. The coin hopper 100 is in this instance provided with a bottom plate 101 which serves as a rest for the coins, and a slideway for the ejector 102. The front edge 103 of the ejector in this instance, contacts with the lowermost coin 104 in the hopper, so as to push this coin from off the support 101 upon the outward movement of the ejector. It will be understood that such an ejector may be substituted for any of the ejectors shown for instance in Fig. 2 of the drawings, if desired.

While I have shown and described a preferred embodiment of my invention, it will be understood that it is not to be limited to all the details shown but is capable of modification and variation within the spirit of the invention and within the scope of the appended claims.

What I claim is:

1. In a change making machine, a plurality of operating members, means for directing a coin successively past said members until one thereof is selected by the coin, a plurality of coin stacks, means for causing the ejection of coin from certain of said stacks upon the actuation of each of said operating members, and means for ejecting slugs from said mechanism of different diameters than the coins normally intended to operate the

same, said members remaining inoperative during the ejection of the slugs.

2. In a change making machine, a frame, a plurality of slides movably mounted therein, one above the other, said slides being provided with registering openings of varying sizes and increasing in size from the lowermost to the uppermost slide, means for guiding a deposited coin into said openings whereby it may fall freely through the slides until lodged in the opening of the proper size to retain the coin, an operating member for moving said slides through the agency of the coin when the coin is of a predetermined size, a plurality of coin stacks, and means connected to said slides to deliver coins from said stacks to the depositor according to the denomination of the deposited coin.

3. In a change making machine, a single coin depositing slot, a plurality of change mechanism operating members, a plurality of coin magazines, means by which a coin deposited in said slot will be delivered to the corresponding operating member, means for engaging the coins to operate the last named members; a slot closing member, and means whereby the slot closing member will be actuated to close the slot during the operation of the change mechanism, regardless of the denomination of the deposited coin, and means for retaining said slot closing member in position to close the slot when the supply of change coins in any of the magazines is exhausted.

4. In a change making machine, a coin slot, coin selected mechanism for delivering change to the depositor according to the denomination of the deposited coin, said mechanism including change ejecting means and means for holding coins of certain sizes in position to operate said ejecting means, said holding means holding coins of other sizes upon insertion thereof in the mechanism in position to be returned to the depositor, and means to return such coins of other sizes to the depositor upon operation of said mechanism without operation of the change ejecting mechanism.

5. In a change making machine, a plurality of coin stacks, coin controlled means for ejecting coins from said stacks, and means for holding said coin controlled means against operation when the level of the coins in said stacks reaches a predetermined position, comprising ejector mechanism, said stacks being provided with slots therein and means on said ejector mechanism to engage in said slots.

6. In a change making machine, a coin stack, an ejector for ejecting coins from said stack, an actuating member connected to and operating with said ejector and adapted to receive and temporarily support a coin of a particular denomination, means adapted to engage a coin of the particular denomination

- when supported in said member and by pressure on the coin to actuate said member, said means being adapted to eject a slug of larger diameter than the coin of the particular 5 nomination from the first named member without producing movement of the ejector.
7. In a change making machine, a coin stack, an ejector for ejecting coins from said stack, a slide for operating said ejector, said 10 to said ejector and adapted to actuate the same, said member having a slot therein adapted to receive and temporarily support a coin of a particular denomination, and means adapted to engage a coin of the 15 particular denomination when supported in said slot, and by pressure on the coin to actuate said slidably mounted member, said means being adapted to eject a slug of larger diameter than the coin of the particular denomination, without causing the actuation of said 20 slidably mounted member.
8. In a change making machine, a plurality of slides having therein registering openings of varying sizes, means providing a coin 25 slot to direct a coin into said openings, means to retain the deposited coin in one of said openings according to the size thereof, a plurality of coin stacks, means to cause coins to be ejected from certain of said stacks by the 30 operation of said slides, and means for ejecting slugs of different diameters than the coins normally intended to operate the machine without causing the operation of said slides.
9. In a change making machine, a coin 35 stack, an ejector for ejecting coins from said stack, a member for operating said ejector, said member being provided with a slot to receive a coin of a particular denomination, 40 means on said member for supporting the coin of particular denomination in the slot, and means for engaging a coin when so supported and through pressure thereon to operate said member, said supporting means permitting the passage of a slug of greater 45 weight than the coin of a particular denomination through the slot without causing the operation of said member.
10. In a change making machine, a coin 50 stack, an ejector for ejecting coins from said stack, a member for operating said ejector provided with a slot adapted to receive therein a coin of a particular denomination, 55 means for supporting the coin of particular denomination in said slot in a predetermined position, means for engaging the coin when so supported and by pressure thereon to operate said member, said last named means ejecting slugs of different diameter than the coin 60 of particular denomination when supported in the slot in positions other than the predetermined position, said supporting means permitting slugs of the same diameter, but 65 greater weight than the coin of particular denomination to pass through the slot, the slugs
- being ejected without causing the operation of said member.
11. In a change making machine, a coin stack, an ejector for ejecting coins from said stack, a slide for operating said ejector, said 70 slide being provided with a slot adapted to receive a coin of a particular denomination, the size of said slot being such that the coin of the particular denomination may pass therethrough, a spring finger on the lower 75 side of said slide extending part way across said slot and adapted to support a coin of the particular denomination therein, and means for engaging a coin when so supported, and by pressure thereon to operate said slide. 80
12. In a change making machine, a coin stack, an ejector for ejecting coins from said stack, a slide for operating said ejector, said slide being provided with a slot adapted to receive a coin of a particular denomination, 85 the size of said slot being such that a coin of the particular denomination may pass therethrough, a spring finger on the lower side of said slide extending part way across said slot, said spring finger being adapted to support a coin of the particular denomination in said slot but adapted to yield and permit the passage therethrough of a slug of greater weight than the coin of particular denomination, and means for engaging a coin 90 when supported in said slot, and by pressure thereon to actuate said slide.
13. In a change making machine, a plurality of slides having therein registering 95 slots of varying sizes, means providing an opening to direct a coin into said slots, means to retain a deposited coin in one of said slots according to the size thereof, a plurality of reciprocable members mounted one above each of said slides and adapted to engage 100 coins supported in said slots and by pressure thereon to actuate said slides, a plurality of coin stacks, and means actuated by said 105 slides for ejecting coins from said stacks.
14. In a change making machine, a plurality of slides having therein registering 110 slots of varying sizes, means providing an opening to direct a coin into said slots, means to retain a deposited coin in one of said slots according to the size thereof, a plurality 115 of reciprocable members mounted one above each of said slides and adapted to engage coins supported on said slides and by pressure thereon to actuate said slides when the coins are of a predetermined size and to 120 eject the coins when they are of greater than the predetermined size, a plurality of coin stacks, and means actuated by said slides for ejecting coins from said stacks.
15. In a change making machine, a plurality of slides having therein registering 125 slots of varying sizes, means providing an opening to direct a coin into said slots, means to retain a deposited coin in one of said slots according to the size thereof, means 130

for engaging coins when so supported and by pressure thereon to actuate said slides, a plurality of coin stacks, means for ejecting coins from said stacks upon movement of said slides in one direction, and means for ejecting the coins from said slots upon movement of said slides in the opposite direction.

16. 16. In a change making machine, a plurality of slides having registering slots therein of varying sizes, means providing an opening to direct a coin into said slots, means to retain a deposited coin in one of said slots according to the size thereof, means for engaging a coin when so supported and by pressure thereon to actuate said slides, a plurality of coin stacks, and arms carried on said slides adapted to engage coins in said stacks and upon actuation of said slides to eject the coins.

17. 17. In a change making machine, a plurality of slides having registering slots therein of varying sizes, means providing an opening to direct a coin into said slots, means to retain a deposited coin in one of said slots according to the size thereof, means for engaging a coin when so supported and by pressure thereon to actuate said slides, a plurality of coin stacks, and arms carried on said slides and adapted upon actuation thereof to eject coins from said stacks, certain of said arms being adapted to engage other arms to effect a simultaneous actuation thereof.

In witness whereof, I have hereunto set
35 my hand this 26 day of June, 1924.
WILLIAM H. RUSSELL.
